UNITED STATES PATENT OFFICE.

SIDNEY J. SYDNEY, OF PHILADELPHIA, PENNSYLVANIA, ASSIGNOR OF ONE-THIRD TO
GEORGE W. SNYDER AND ONE-THIRD TO GEORGE A. GALE, BOTH OF PHILADEL-
PHIA, PENNSYLVANIA.

INTERNAL-COMBUSTION ENGINE.

1,086,243.

Specification of Letters Patent. Patented Feb. 3, 1914.

Application filed November 21, 1912. Serial No. 732,761.

To all whom it may concern:

Be it known that I, SIDNEY J. SYDNEY, a citizen of the United States, residing at Philadelphia, in the county of Philadelphia and State of Pennsylvania, have invented certain new and useful Improvements in Internal-Combustion Engines; and I do hereby declare the following to be a full, clear, and exact description of the invention, such as will enable others skilled in the art to which it appertains to make and use the same.

My invention relates to improvements in internal combustion engines, and it consists in the constructions, combinations and arrangements herein described and claimed.

An object of my invention is to provide an improved ignition device adapted for efficient use with all types of internal combustion engines, and which can be readily adjusted for timing the ignition.

A further object of my invention is to provide an improved ignition device for internal combustion engines, which will insure a more positive and certain ignition than has been possible in previous constructions.

In the accompanying drawings forming a part of this application, and in which similar reference symbols indicate corresponding parts in the several views:—Figure 1 is an axial section of the power cylinder of a two-cycle engine, with one embodiment of my invention applied thereto; Fig. 2 is an enlarged detail section on the line 2—2 of Fig. 1; and Fig. 3 is an axial section of the power cylinder of a four-cycle engine, with my invention applied thereto.

Referring to the drawings, 1 indicates a small auxiliary cylinder carried by the power cylinder 2 of a two-cycle engine, and communicating with the compression end of the latter by a duct 3 controlled by a valve 4; an auxiliary piston 5 being shown attached to the engine piston 6 for compressing a fluid in said auxiliary cylinder 1. The cylinder 1 is preferably provided with a check valve 1^a for permitting the entrance of air.

When the intake is throttled or cut off during one or more reciprocations of the power piston, as by a governor, the gas supply from the power cylinder 2 to the compression cylinder 1 may be in so at-

tenuated a condition as to be insufficient in density to have its temperature raised to the ignition point of the explosive mixture; therefore, the valve 1^a is employed for admitting under such conditions a sufficient quantity of air to the compression cylinder 1 to provide a sufficient density for insuring a temperature upon compression in said cylinder above the ignition point of the explosive mixture.

A lever 7 is pivoted at 8 on a bracket 9 carried by the auxiliary cylinder 1, and is provided with a forked end for actuatingly engaging a head 10 on the stem 11 of said valve 4; a spring 12 being secured under tension to said lever 7 for yieldingly maintaining the valve 4 seated in closed position. An adjustable stop 13 is provided with a projection 14 slidably mounted in a slot 15 in said lever 7; a thumb screw 16 being provided for locking said stop 13 in its several adjusted positions for engagement by an arm 17 carried by the auxiliary piston 5. The parts are preferably so constructed that the stop 13 will be shifted from the path of said arm 17 when the lever 7 has been swung to fully open the valve 4.

The above described construction provides a compact construction, in which the valve 4 and its actuating mechanism are carried directly by the auxiliary cylinder 1; thereby constituting a self-contained device adapted to be conveniently secured in position on the engine cylinder.

In the operation of the above described device, the auxiliary piston 5 will be forced outwardly during the power stroke of the engine piston 6, and expand the gaseous fluid in the relatively small auxiliary cylinder 1 to a pressure below that in the engine cylinder 2; thereby causing the excess of pressure in said engine cylinder to open the spring-seated valve 4 and fill said auxiliary cylinder with the gaseous products from the engine cylinder during the power stroke. If the supply of explosive mixture to the engine cylinder 2 should be excessively throttled or cut off, air would be drawn into the auxiliary cylinder 1 through the check valve 1^a during the out stroke of the auxiliary piston.

During the compression stroke of the engine piston 6, the gaseous fluid in the auxiliary cylinder 1 will be compressed by the

auxiliary piston 5 to the ignition point of the explosive charge, and the valve 4 will be maintained firmly closed by the excess of pressure in said auxiliary cylinder; such excess of compression in the auxiliary cylinder being readily insured by the small clearance space at the upper end of said cylinder. The compression cylinder 1 is arranged to compress air to the ignition point of the explosive mixture; hence, when compressing the hot gases of the previous explosion it will raise said hot gases to a temperature above the ignition point of the explosive mixture, and thus insure a large factor of certainty in the ignition during normal operation of the engine. The arm 17 then engages the stop 18 and swings the lever 7 to open the valve 4 for discharging a jet of hot gaseous fluid from the auxiliary cylinder 1 at high velocity through the compressed charge in the engine cylinder 2; thereby insuring a positive and efficient ignition of said charge. In my improved construction, the pressure in the auxiliary cylinder 1 maintains the valve 4 firmly seated to prevent all leakage losses of the high pressure fluid from said cylinder; thereby avoiding the irregular and inefficient action found to occur in previous construction, and insuring a positive and certain ignition under all operative conditions.

Referring especially to Fig. 3 of the drawings, 18 indicates a small auxiliary cylinder carried by the power cylinder 19 of a four cycle engine, and communicating with the compression end of the latter by a duct 20 controlled by a valve 21; said valve being yieldingly maintained seated by a spring 22 connected to a bent lever 23, which latter is pivoted on a bracket 24 on the auxiliary cylinder 18 in position to actuatingly engage a head 25 on the valve stem 26.

A piston 27 is mounted in the auxiliary cylinder 18 for compressing a fluid therein to the ignition point of the explosive charge; said piston acting to control a port 28 between said cylinders 18 and 19. A lever 29 is fulcrumed at 30 and connected by a link 31 with said auxiliary piston 27; said lever 29 being connected by an intermediate link 32 with an arm 33 pivoted at 34 on an adjustable lever 35 fulcrumed at 36.

A cam 37 is driven from the main engine shaft by a two to one gearing, or other usual means, and adapted to engage a roller 38 on the arm 33 to swing the latter into engagement with the bent lever 23 for shifting the valve 21 to open position; such swing of said arm 33 acting also to actuate the auxiliary piston 27. The roller 38 is maintained in engagement with the cam 37 by a spring 39 connected under tension to the lever 29; the lever 35 being readily adjusted about its

fulcrum 36 to vary such engagement between said cam and roller.

In the operation of a four-cycle engine, the roller 38 will travel on the low semi-circular portion of the cam 37 during the exhaust and admission strokes of the engine piston. During the compression stroke the roller will ride up the high portion 40 of the cam, thereby swinging the arm 33 to compress a gaseous fluid in the auxiliary cylinder 18 and finally to engage the bent lever 23 to suddenly open the valve 21 upon completion of the compression stroke. During the power stroke, the roller 38 will initially ride over the high segment 41 of the cam 37, and during the last half of the stroke travel over the portion 42 of said cam to the low portion of the latter. In this engagement of the roller 38 during the power stroke of the engine, a portion of the products of combustion will be forced from the engine cylinder past the spring-seated valve 21 into the auxiliary cylinder 18, and the pressure in said two cylinders will be further equalized upon opening of the port 28 by the auxiliary cylinder 27 at the final portion of the power stroke.

I have illustrated and described preferred and satisfactory constructions, but changes could be made within the spirit and scope of my invention.

I claim:—

1. In combination with an internal combustion engine, an auxiliary cylinder communicating with the engine cylinder, a piston for compressing a fluid in said auxiliary cylinder to the ignition point of the explosive charge, a spring-seated valve in such communication adapted to be maintained closed by the pressure in said auxiliary cylinder, and actuating means for shifting said valve to open position.

2. In combination with an internal combustion engine, an auxiliary cylinder communicating with the engine cylinder, a piston for compressing the fluid in said auxiliary cylinder to the ignition point of the explosive charge, a spring-seated valve in such communication adapted to open under excess of pressure in the engine cylinder and to be maintained closed by an excess of pressure in said auxiliary cylinder, adjustable means for positively shifting said valve to open position, and means carried by said piston for actuatingly engaging said adjustable means.

In testimony whereof, I affix my signature, in presence of two witnesses.

SIDNEY J. SYDNEY.
